DIE CASTING MACHINE

Frederick Gash, Carlisle, England, assignor to
 William Coulthard & Company Limited, Carlisle, England, a British company

Application August 13, 1948, Serial No. 44,150
 In Great Britain September 27, 1947

3 Claims. (Cl. 22—70)

1

This invention is for improvements in or relating to die-casting, moulding or like machines of the kind (hereinafter called the kind specified) comprising a device known as a "gooseneck" or the like the metal or other material being forced through the gooseneck and injected into the dies. In one such machine of this kind the throat part of the gooseneck and a plunger or piston which works therein and acts to force the metal through the gooseneck and into the dies, are immersed in a pot containing the molten metal or other material from which the castings are made.

One object of the present invention is to provide an arrangement for securing or locating the gooseneck on the machine, which arrangement will not seriously interfere with expansion and contraction of the gooseneck under changes of temperature.

A further object of the present invention is to provide a mounting arrangement for the gooseneck which facilitates the location of the gooseneck in correct alignment with other parts of the machine.

Heretofore, it has been the practice to mount and support the gooseneck in such a manner that no satisfactory facilities are available for readily centering or aligning said gooseneck correctly with respect to its associated parts of the machine. One arrangement used heretofore consists of two clamping set-screws adapted to fit into dimples machined in the gooseneck wings. With such an arrangement difficulty is inevitably experienced in obtaining the correct alignment of the gooseneck if there is the slightest error in the machining of the dimples. Furthermore, this arrangement does not permit the desired free expansion and contraction of the gooseneck under changes of temperature.

According to the present invention the gooseneck is secured or located on the machine by resilient means which will allow for expansion and contraction of the gooseneck.

According to a further feature of the present invention there is provided a die-casting or like machine of the kind specified wherein means is provided for adjusting the gooseneck or equivalent or like device horizontally in at least two directions at right angles to one another.

From another point of view, the present invention provides a die-casting machine or the like of the kind specified and of the plunger type, wherein means is provided for adjusting the gooseneck or equivalent or like device in at least two directions at right angles to one another, and in a common horizontal plane normal to the axis

2

of the piston or plunger so that the part of the gooseneck which receives said piston or plunger can be set in alignment therewith.

Conveniently, the locating device includes a resilient part adapted to allow for relatively free expansion and contraction of the gooseneck under changes of temperature such as obtained in die-casting machines.

One specific embodiment of the invention will now be described, by way of example, with reference to the accompanying drawings. On the drawings:

Figure 1 is a perspective elevation of a die-casting machine of well known form but incorporating the improvements according to the present invention.

Figure 2 is a transverse sectional elevation of the machine shown in Figure 1 the section being taken through the metal pot and gooseneck hereinafter referred to.

Figure 3 is a fragmentary sectional elevation on the line III—III of Figure 2.

Figure 4 is a fragmentary elevation to an enlarged scale of the gooseneck aligning means viewed in the direction of the arrow IV in Figure 3, and

Figure 5 is a fragmentary plan view of the gooseneck aligning means, the view being taken in the direction of the arrow V in Figure 3.

The machine shown in Figure 1 of the drawings is similar in most respects to various known forms of die-casting machines of the kind concerned except as regards the means provided for effecting correct alignment and location of the gooseneck with respect to its associated parts of the machine.

Briefly, the machine shown in Figure 1 of the drawings comprises a frame 10 supporting the dies 11 (see Figure 2), the dies being opened and closed in the usual way, say, by a hand-wheel 12 or by pressure fluid operated means. 13 indicates the pot for the molten metal which, together with the heating means 14 forms the furnace assembly. This assembly is pivoted at 15 on the machine frame and is adapted to be rocked about its pivotal support 15 automatically with the closing of the dies in the usual way so as to bring the nozzle 17 of the gooseneck 18 (see Figure 2) into register with the sprue 19 of the dies 11 when a "shot" or die-casting operation is to be effected. The gooseneck 18 is formed with a cylinder 20 immersed in the molten metal in the pot 13 and having a port 21 through which the molten metal flows into the cylinder 20. A plunger 22 works in the cylinder 20 in the usual way to inject the

molten metal, via the gooseneck and sprue opening 19, into the dies. The plunger 22 is operated by an air piston and cylinder device 23 (see Figure 3) mounted on an air cylinder support 24 which is supported in turn on the furnace assembly and is bolted thereto by means of bolts 25 (see Figures 1 and 4). The gooseneck 18 is supported by its lugs or wings 26 (see Figure 3) which rest on the upper face of the metal pot 13 and pass through arches 27 in the lower part of the air cylinder support 23, as shown more particularly in Figures 1 and 4. The lugs or wings 26 of the gooseneck are held down on the upper surface of the metal pot by means of clamping bolts 28 (see Figure 3). Prior to the tightening up of these clamping bolts the gooseneck has to be adjusted so that the cylinder 20 is in correct alignment with the plunger 22 and other associated parts of the machine. To effect adjustment of the gooseneck laterally, there is provided, for the purpose of the present invention, two inverted L-shaped brackets 29, positioned on diametrically opposite sides of the gooseneck one adjacent each gooseneck wing, as shown more particularly in Figures 1 and 3. The brackets 29 are made of steel or like resilient material and are secured to the air cylinder support 24 by the studs or bolts 25 which, as stated above, serve to secure the air cylinder support to the furnace assembly. The vertical part 30 of each of the brackets 29, is fitted with an adjusting screw 31 the forward end of which bears on the neighbouring vertical edge of the gooseneck wing. Nuts 32 are provided on the adjusting screws 31 for locking them in their position of adjustment. In addition to the aligning screws 31 just described, the usual adjusting screws 33 are provided (see Figure 2) for adjusting the gooseneck towards and away from the sprue of the dies (sufficient clearance being provided in the arches 27 to enable this to be done) and also for taking the thrust of the gooseneck, the screws 33 being screwed through the air cylinder support 24. Thus, the gooseneck is adjustable in two directions at right-angles and in a common horizontal plane.

By adjusting the screws 31 and the screws 33 adjustment of the gooseneck, where necessary, can be effected in both directions in the horizontal plane so as to bring the cylinder 20 of the gooseneck into precise alignment with the plunger or piston 22 and allow a free movement of the latter in the cylinder. After the necessary adjustment has been made, the locating screws 31 and 33 are locked in position so as to maintain correct location of the gooseneck and the clamping screws 28 are tightened down.

In the direct air type of machine it is convenient to secure the brackets 29 to the metal pot cover.

Trouble has been experienced in the past due to the bore 20 of the gooseneck not being easily alignable with the piston or plunger 22 and the axis of the air cylinder 23. The L-shaped bracket arrangement just described makes it possible to align the gooseneck with the piston or plunger and its other associated parts of the machine, quickly and easily. This is of great advantage to the user of the machine when a new gooseneck has to be fitted. Furthermore, there is a certain amount of spring inherent in the L-shaped brackets, which should be made from a suitable material, to allow for any difference in expansion or contraction between the gooseneck and its associated parts of the machine, due to tempera-

ture variations between the various parts. This overcomes the objection referred to above regarding the matter of relatively free expansion and contraction of the gooseneck. This feature of the invention makes the invention applicable to the direct air type of machine as well as the plunger type. In the former type the invention is of advantage because it allows for expansion and contraction of the gooseneck across the gooseneck lugs or wings 26.

I claim:

1. In a die-casting machine of the type having a sprue opening for the dies, a furnace assembly including a melting pot, a gooseneck having an outlet nozzle for cooperation with said sprue opening and including a throat part in communication with said nozzle and positioned in said melting-pot by lateral wings on opposite sides thereof and resting on the opposite sides of said furnace assembly, a piston device for operating a plunger in said throat and including a support mounted in fixed relation on said furnace assembly and carrying adjustable screw devices in engagement with the sides of said lateral wings for adjusting the gooseneck nozzle toward the sprue opening, and means for clamping the gooseneck to said furnace assembly in adjusted position, the improvement which comprises a horizontally disposed adjustable screw device supported in fixed relation on each side of said furnace assembly and in engagement with the end of the adjacent lateral wing for adjusting the gooseneck nozzle laterally with respect to said sprue opening.

2. In a die-casting machine of the type having a sprue opening for the dies, a furnace assembly including a melting pot, a gooseneck having an outlet nozzle for cooperation with said sprue opening and including a throat part in communication with said nozzle and positioned in said melting-pot by lateral wings on opposite sides thereof and resting on the opposite sides of said furnace assembly, a piston device for operating a plunger in said throat and including a support having arched feet mounted in fixed relation on opposite sides of said furnace assembly with said feet straddling said lateral wings and carrying horizontally disposed adjustable screw devices in engagement with the sides of said lateral wings for adjusting the gooseneck nozzle toward the sprue opening, and means for clamping the gooseneck to said furnace assembly in adjusted position, the improvement which comprises an inverted L-shaped bracket supported by each of said arched feet and having a resilient downwardly extending limb in front of and parallel to the end of the lateral wing straddled by the respective foot, and a horizontally disposed adjustable screw device supported by each of said depending limbs and in engagement with the end of the respective lateral wing for adjusting the gooseneck nozzle laterally with respect to said sprue opening.

3. In a die-casting machine of the type having a sprue opening for the dies, a furnace assembly including a melting pot, a gooseneck having an outlet nozzle for cooperation with said sprue opening and including a throat part in communication with said nozzle and positioned in said melting-pot by lateral wings on opposite sides thereof and resting on the opposite sides of said furnace assembly, a piston device for operating a plunger in said throat and including a support mounted in fixed relation on said furnace

assembly and carrying adjustable screw devices in engagement with the sides of said lateral wings for adjusting the gooseneck nozzle toward the sprue opening, and means for clamping the gooseneck to said furnace assembly in adjusted position, the improvement which comprises a resilient support in fixed relation on each side of said furnace assembly, and a horizontally disposed adjustable screw device carried by each resilient support and in engagement with the 10 end of the adjacent lateral wing for adjusting the gooseneck nozzle laterally with respect to said sprue opening.

FREDERICK GASH.
